UNITED STATES PATENT OFFICE

2,609,600

CONTAINER OPENER

William D. Husted, Shavertown, Pa.

Application December 16, 1948, Serial No. 65,551

3 Claims. (Cl. 30—16)

1

This invention relates generally to openers for cans or other like containers and which operates by puncturing a hole in the top of the can or container.

An object of this invention is to provide an opener for cans or containers which punctures the top wall thereof and in which the size of the hole punctured thereby may be regulated, so as to provide an opener which may puncture a relatively large hole for pouring, and by means of a simple adjustment be adapted to puncture a relatively small vent hole in the top wall.

A further object of this invention is to provide a can opener having a puncturing point thereon and can rim gripping means, and in which the distance from the point to the rim gripping means may be adjusted for the purpose of regulating the size of the punctured hole.

Another object of this invention is to provide a puncturing type can opener having a puncturing point formed on one end thereof, and a can or container rim gripping device which is so constructed as to be slidably carried by the handle of the opener for motion towards and away from the puncturing point in order to regulate the size of the hole formed in the top wall of the can or container.

An additional object is to provide a can opener having the above characteristics and so constructed as to be adaptable to be formed of stamped parts thus securing a sturdy and inexpensive adjustable puncturing type opener.

With these and other objects in mind my invention consists of the combination and details of construction described in the following specification, and shown in the accompanying drawings, and more particularly defined in the appended claims.

In the drawings,

Figure 1 is a side elevation of an embodiment of my invention, showing the can opener positioned against the rim of a can or container in puncturing relationship thereto,

Figure 2 is a top plan view of the opener shown in Figure 1, the handle of the opener is shown as broken to illustrate that the length of the handle may be varied,

Figure 3 is a detail sectional view taken on the line 3—3 of Figure 1,

Figure 4 is a fragmentary detail sectional view taken on the line 4—4 of Figure 3,

Figure 5 is a side elevation of a modification of the can opener shown in Figure 1, showing the hole puncturing end thereof,

Figure 6 is a bottom plan view of the can opener shown in Figure 5; and

2

Figure 7 is a sectional view taken on the line 1—1 of Figure 5.

Referring to the drawings and first to Figures 1, 2, 3 and 4, a puncturing type can opener constructed according to an embodiment of my invention is there illustrated. The opener consists of an elongated handle member 20 having a downwardly angled tapered forward blade portion 21. The forward end of the angled portion 21 is formed with an offset point 22 for cutting or puncturing a hole in the top wall of a container or can. An elongated longitudinally extending slot 23 is formed in the angled portion 21 of the handle 20. The handle 20 is formed with a struck out downwardly angled lug 24 which may be used as a bottle cap remover.

For the purpose of providing container rim gripping means, a U-shaped member 25 having vertically disposed spaced apart side walls 26 is positioned in the slot 23. The side walls 26 are joined together along the bottom edge thereof by the bight portion 27. The U-shaped member 25 is formed of a resilient metal, such as spring steel, and the side walls 26 will be constantly urged against the side edges 28 of the slot 23. The top edges of the walls 26 are bent outwardly at right angles thereto to provide a pair of opposed flanges 29 adapted to slide along the top surface of the handle portion 21 on the opposite sides of the slot 23. The rear edges of the side walls 26 are formed with notches 30 adjacent the top thereof, and the lower edges 31 of the notches 30 are bent outwardly, as seen in Figure 3, to engage the bottom surface of the handle portion 21 on the opposite sides of the slot 23 to restrict upward movement of the U-shaped member 25 relative to the handle portion 21. The forward edges of the side walls 26 are formed with cut-outs 32, providing a hooked member 33 on each of the side walls for gripping engagement under the rim of a can or container. The container rim gripping means is assembled to the handle 20 by inserting the bight end of the U-shaped member 25 into the slot 23 from above and then pressing downwardly on the flanges 29, the side walls 26 will be deflected towards each other to allow the bent out edges 31 of the notches 30 to pass through the slot. Once the bent out edges 31 are through the slot 23, the side walls 26 will snap apart, thus containing the side edges 28 of the slot between the flanges 29 and the bent out edges 31. When it is desired to disassemble the rim gripping means from the handle, the side walls 26 are pressed together and the U-shaped member merely lifted out of the slot 23.

55 The operation of my puncturing type can

opener is as follows: As seen in Figure 1 of the drawing, the hooked members 33 are engaged under the rim or bead B formed about the top edge of the can or container A puncturing or cutting a hole therein. If a large hole is desired, the member 25 is moved to the rear end of the slot 23, thus positioning the point 22 a considerable distance inwardly from the rim D. If a relatively small hole is desired, the member 25 is moved to the forward end of the slot 23, and the point 22 is positioned close to the rim or bead B. It can be seen, therefore, that the position of the member 25 relative to the slot 23 will control the size of the punched hole.

In Figures 5, 6 and 7, I have illustrated a modification of my invention in which I have varied the construction of the rim gripping means. The rim gripping means 34 consists of a plate 35 disposed on the top surface of the angled portion 21 of the handle 20. A pair of downwardly extending ears 36 are formed integrally with the side edges of the plate 35. A lug 37 is struck down from the forward edge of the plate 35 to engage within the slot 23. A cut-out 38 formed in the rear edge just below the cut-out 38 is bent inwardly, as at 39, to engage under the outer edge 40 of the handle portion 21. The ears 36 are tapered towards the bottom and are formed with circular cut-outs 41 in the forward edge adjacent the top thereof to provide hooked members 42. As can be seen in Figure 7, the ears 36 are spaced outwardly of the side edges 40 of the handle portion 21. Therefore, the hooked members 42 are also spaced apart a substantial distance, and when the hooked members 42 are positioned in gripping engagement with the under side of the rim B on a container A, the spaced apart hooked members 42 will assure the proper positioning of the point 22 on a radius of the circular top of the container. In assembling the can opener shown in Figures 5, 6 and 7, the rear edges of the ears 36 are bent in, as at 39, only after the plate 35 has been positioned on top of the portion 21 with the lug 37 engaging in the slot 23, and once so bent will prevent separation of the member 34 and the handle 20.

The lug 37 will engage against the forward or rear end of the slot 23 to limit the sliding travel of the rim gripping means relative to the handle member 20.

The above description pertains to several embodiments of my invention which I have found to be fully capable of performing the stated objects, however it is understood that various modifications and differences in construction may be resorted to without departing from my invention as defined by the appended claims.

What I claim is:

1. A can opener comprising a flat tapered blade

formed with an offset obtusely disposed puncturing point and having a longitudinal slot therein, and a can rim engaging means slidably mounted on said blade for adjustment relative to said point, said can rim engaging means including a U-shaped member slidably disposed in said slot, means on said member extending over the top of said blade, means on said member adapted to engage the bottom surface of said blade, and hooked portions formed on the parallel sides of said member for engaging a can rim.

2. A can opener comprising a flat tapered blade formed with an offset obtusely disposed puncturing point and a longitudinal slot, and can rim engaging means slidably mounted on said blade for adjustment relative to said point, said means including a resilient U-shaped member extending downwardly through said slot, a pair of opposed flanges formed on said U-shaped member extending over said blade, outwardly struck portions on said member adapted to engage the bottom surface of said blade and cooperating with said flanges to slidably hold said member on said blade, and hooked means on the parallel sides of said member adapted to engage a can rim.

3. A can opener comprising a flat tapered blade formed with an offset puncturing point and a longitudinally extending slot, and can rim engaging means slidably mounted on said blade for adjustment relative to said point, said means including a pair of spaced apart side members resiliently joined together along the bottom edge thereof and formed with opposed outwardly directed flanges integral with the top edge thereof, said flanges engaging the top surface of said blade and said side members extending downwardly through said slot, outwardly bent portions formed on the rear edge of said side members adapted to engage under said blade for retaining said side members in said slot and cooperating with said flanges to slidably hold said member on said blade, and hooked means on the forward edges of said side members adapted to engage a can rim.
